UNITED STATES PATENT OFFICE.

VLADIMIR KARAPETOFF, OF ITHACA, NEW YORK.

MAXIMUM-DEMAND METER

972,538.

Specification of Letters Patent. Patented Oct. 11, 1910.

Application filed November 9, 1907. Serial No. 401,474.

To all whom it may concern:

Be it known that I, VLADIMIR KARAPETOFF, a subject of the Emperor of Russia, residing at Ithaca, in the county of Tompkins and State of New York, have invented certain new and useful Improvements in Maximum-Demand Meters, of which the following is a specification, reference being had to the accompanying drawings.

10 My invention relates to improvements in electric meters commonly known as maximum-demand meters.

An object of my invention is to provide a meter of the class described which will have 15 a wide range of adaptability to the varying conditions of use to which it may be put.

One feature of my invention is the provision of electromagnetic means for the release of the pointed-positioning device from 20 the wattmeter and the restoration of the former, together with the maximum-indicating pointer, to its initial position. The electromagnetic device which releases and 25 resets the pointer-positioning device is separate from the electromagnetic device which resets the maximum-indicating pointer.

Another feature of my invention lies in the provision of means for adding the periodic maximum displacements of the maximum-indicating pointer; that is, the maximum displacements in a period of, say, twenty-four hours is added to the maximum displacement occurring in the next twenty-four hour period and so on, whereby at the 30 end of the longer period, for which the bills are made out, the latter may be based upon the monthly sum of these displacements (or maximum power-demands) or upon this sum divided by the number of 40 days in the month.

A third feature of my invention resides in the provision of means for imposing upon the consumer a penalty for using power in excess of the stipulated maximum. This 45 may be done by giving to the pointer a displacement equal to the product of a multiplier and the displacement of the pointer-positioning device during that part of the travel of the device which occurs during a 50 use by the consumer of power in excess of the stipulated amount. Means are also provided to carry out terms which appear in some agreements stipulating that the allowable maximum shall vary with the hour of 55 the day and with the day of the week.

A further feature of my invention con-

sists in the provision for adding the periodic excess power-demands over the allowable maximum power-demand stipulated by the agreement; that is, instead of adding the 60 periodic maximum displacements, only the periodic excesses of these maximum displacements over the allowable maximum are added. In case the excess exceeds an allowable amount, a penalty may be imposed, as hereinbefore stated.

Other features of my invention will be set forth in the description which follows hereinafter.

In the drawings illustrating the principle 70 of my invention and the best mode now known to me of applying that principle, Figure 1 is an elevation, partly in section, of my new maximum-demand meter of which some of the parts are shown conventionally; 75 Fig. 1^a is a view entirely similar to Fig. 1 but showing a modified form in which mechanism is provided moving the guard-plate; Fig. 2 is a detail of the delayed-action make-and-break device; Fig. 3 is a detail showing 80 a modification of the make-and-break device of Fig. 2; Figs. 4 and 5 are details showing the electromagnetic device for restoring the push-arm or positioner to its initial position; Fig. 6 is a detail of a modified form of the 85 mechanism for restoring the push-arm to its initial position; Fig. 7 is a plan view of Fig. 8 is a section on the line A—A of Fig. 1^a; Fig. 9 is a section on the line B—B of Fig. 1^a; Fig. 10 is a detail in plan 90 of the manually-adjustable guard-plate used in the apparatus shown in Fig. 1; and Fig. 11 is a detail of a modified form of a device for moving the guard-plate.

The integrating wattmeter *a* is connected 95 with and drives my new meter through its shaft *b* provided with a pinion *c* which meshes with a toothed wheel or gear *d*. Upon the same shaft with the latter is a pinion *e* which drives a toothed wheel *f* fast 100 upon the driving shaft *g* of my new meter. The last-named shaft carries the lower member *h* of a friction-clutch the upper member *i* of which is provided at its top with an armature *j* the peculiar form or shape of 105 which is best shown in Figs. 4 and 5. The armature *j* lies between pole-pieces *k* which are momentarily energized from time to time, (say, at one-minute intervals) by a current made to flow through the coil *m*. 110 An L-shaped positioner or push-arm *n* is carried by the armature *j* on the lower end

of which is mounted the aforesaid upper member *i* of the friction-clutch; and the free upper end of the arm *n* is adapted to engage and push against the horizontal part *p* of a maximum-demand indicator or pointer *q*. The latter is mounted upon the shaft *r* which carries also an armature *s* which closely resembles in shape the armature *j*, hereinbefore referred to. The armature *s* lies between the pole-pieces *t* which are energized momentarily from time to time (say, at intervals of twenty-four hours) by a current made to flow through the coil *u*. The index end *v* of the pointer *q* travels over the graduated limb of a dial *w* and gives the readings indicated by the figures on the outer edge of the limb. To energize the pole-pieces *k* a contact-clock *x* (of any approved type now on the market) may be put in circuit with the coil *m*; or the devices shown in Fig. 6 may be used. Where a contact-clock (shown in the drawings conventionally at *x*) is used, the contact is made at intervals of one minute (a different interval may, of course, be adopted, if desired) and an instantaneous current flows through and energizes the coil *m*, thereby magnetizing momentarily the pole-pieces *k*. The armature *j* is first raised by the attraction of the pole-pieces *k* just enough to free the upper member *i* of the friction clutch from the lower member *h* thereof, after which the armature is thrown from the position shown in Fig. 4 to its initial position shown in Fig. 5. The armature *j* and the upper member *i* of the clutch are loosely mounted or sleeved on the upper end of the driving shaft *g* and the return movement of the armature *j*, clutch-member *i* and push-arm *n* is made without affecting the driving shaft *g* and through it the wattmeter *a*, which will continue to register.

In the modified form shown in Fig. 6, the push arm *n* is carried by a loose collar *y* which is mounted upon the driving shaft *g'* of the meter and is held frictionally between the fast collar or disk *z* and a disk *2* keyed to the shaft *g'* and free to move along the same under the influence of the coil spring *3* one end of which bears against the lower face of the disk *2* and the other end of which bears against a shoulder *4* upon the shaft *g'*. From the loose collar *y* projects a stud or lug *5* to which is attached one end of the cord *6* the other end of which passes over a pulley *7* and is fastened to the lower end of a plunger *8* that projects into the coil *9*. The loose collar *y* is driven by the friction between its upper and lower faces and the disks *z* and *2*, respectively, as the driving shaft *g'* rotates; and it will be understood that the cord *6* is loose while the collar *y* is frictionally held as hereinbefore described. The latter is made of non-magnetic material; and when the contact-clock *x* sends a

current through the coils *9* and *9** at the end of the minute-interval, the coil *9** energizes the pole-pieces *10* which pull down the disk *2* against the tension of the spring *3*. The energized coil *9* pulls within itself the plunger *8*, while simultaneously the coil *9** through the plunger *8* restores the now released collar *y* to its original position. The contact being broken, the plunger *8* drops and the coil spring *3* forces the disk *2* upwardly from the now demagnetized pole-pieces *10*. By suitably shaping the latter, the coil *9** may be dispensed with and the coil *9* used alone to magnetize these pole-pieces.

To restore the push-arm *n* and the pointer *q* to their initial position at the same time, the following devices are provided: The contact-clock *x* drives the shaft *11* upon which is mounted the cam *12* formed with a shoulder *13*. The cam *12* makes one revolution every twenty-four hours and at the end of each hour it is advanced one twenty-fourth of a revolution, its motion of rotation being a step-by-step motion and not a motion of uniform rotation; in this way a quicker movement and more sudden action of the cam *12* is obtained. The free end of each of a pair of contact-plates *14* bears upon the cam surface of the cam *12* and these contact-plates are each provided with a contact-block *15*. Below the contact-plates *14* is arranged symmetrically with respect thereto a contact-plate *16* provided with a cross-bar *17*. The base of an L-shaped piece *18* of insulation extends under the lower contact-plate *16*, while the upper end of the insulation *18* is attached to one of the upper contact-plates *14*. In this way the lower contact-plate *16* is prevented from falling away from the upper contact-plates *14*, and at the same time it is free to approach the latter at the proper time. The contact-plates *14*, *16* are each pivotally mounted at one end, as shown in Fig. 2. Between each of the upper contact-plates *14* and the frame-plate *19* are interposed coil springs *20* which tend to pull the contact-plates *14* downwardly and keep their free ends in rubbing contact with the cam *12*. To the lower contact-plate *16* is attached the upper end of a connecting-rod or pitman *21* the lower end of which is connected to a wheel *22*, which through the speed-increasing train of toothed wheels *23*, *24*, *24'* shown in Fig. 2 drives the shaft *25* upon which is mounted a fly wheel *26*. The latter may be replaced by or used in connection with a fan *29*. As the cam *12* continues to rotate in the direction of the arrow in Fig. 2, the shoulder *13* will at the end of the twenty-four hour interval slip from under the free end of the contact-plates *14* and the coil spring *20* will pull the contact-plates *14* downwardly until the contact-blocks *17* makes electrical con-

tact with the cross-bar 15, whereby the circuit will be closed at this point and current will flow through the coils *u* and *m*, energizing the pole-pieces *t* and *k*, and throwing the armatures and the attached pointers *q* and *n* to their initial position. The fly-wheel 26 by its inertia will delay the separation of the lower contact-plate 16 from the upper contact-plates 14 and will allow the current to flow for a longer time than it otherwise would. This delayed breaking of the circuit is for a purpose hereinafter set forth.

From the foregoing description and an inspection of the drawings in connection therewith, it will be obvious that the final position of the pointer *q* will give, when read just before the expiration of the twenty-four hour period, the maximum demand made by the consumer during that period, such maximum demand being taken as the highest consumption of electrical energy in one minute during the period. But it will be understood that the pointer *q* may not be restored to its original position until the end of any other desired period, as a week, a month or a year.

Instead of taking the maximum demand as just described, it may be taken as the average of the highest daily consumptions of electrical energy in one minute (or the average of the highest one-minute "peaks") during any stated period, as one month. In order to adapt my new meter to give such an average highest daily consumption, the armature *s* is formed at its upper edge with ratchet teeth 31 and a pointer-carrying shaft 32 is provided (Fig. 1) the lower end of which is mounted free to turn in a socket 33 formed in the upper end of the shaft *r* upon which is fastened the armature *s*. The pointer-carrying shaft 32 carries at its upper end a pointer or hand 34 and near its lower end a pair of dogs or pawls 35 pivotally mounted on opposite sides of the boss 36. Further, the shaft 32 is provided just below the dial *w* with a pinion 37 which drives the toothed wheel 38 upon the shaft 39 upon the upper end of which is mounted above the dial *w* a pointer 40. During the outward travel of the pointer *q* as the latter is driven, through the push-arm *n*, by the wattmeter *a*, the pawls 35 ride idly over the ratchet teeth 31; but during the return movement of the pointer *q* at the end of the 24-hour period, as hereinbefore described, the pawls 35 engage the teeth 31 and through such engagement the armature *s* turns the pointer-carrying shaft 32 through an arc equal to that traveled by the pointer *q* during its outward (and, of course, its return) movement. The pointer 34 will travel in a clockwise direction and will, in conjunction with the pointer 40, give the sum of all the daily highest power-demands during any

one minute; and this sum divided by the number of days in the month will give the average of the daily highest power-demands for one minute (or the average of the highest one-minute "peaks") upon which the consumer's bill will be based for that month. By suitable reducing gears, (not shown herein) the movement of the pointers 34 and 40 may be made to indicate directly one-thirtieth of the sum of the greatest outward movements of the pointer *q* in one minute and thereby to give the average of the highest one-minute "peaks" during a period of thirty days.

In some contracts between the producer and the consumer, it is stipulated that the consumer shall pay in any event for a certain minimum whether furnished or not; and if this minimum be exceeded, then the consumer pays (1) at the rate of the highest demand for electrical energy during any one minute within the period fixed by the agreement, or (2) at the rate of the average of the daily highest demands during the one-minute intervals in such period. To provide for the first of these two cases just described, a stop pointer 41 is provided the index end of which extends beyond the graduated limb and edge of the dial *w* and lies between the zero of the outer scale and the index end *v* of the pointer *q*. (Fig. 7). It will be obvious that if the push-arm *n* during any one-minute interval travels beyond the reading for which the stop pointer 41 is set, it will carry the pointer *q* with it beyond that reading and the pointer *q* will by its position at the end of the period which has elapsed since the last resetting indicate the maximum power-demand in one minute during that period; and it will also by this position when compared with the set position of the stop pointer 41, give the excess of this maximum power-demand over that for which the customer must in any event pay. The excess power-demand so determined will furnish a basis for the amount charged the consumer for the period. In the second case of the two just described, the pointers 34 and 40 are provided, as hereinbefore described, and they will give by their readings the sum of the daily excess power-demands over the fixed minimum determined by the position of the stop pointer 41. By dividing the sum so found, by the number of days in the period (as a week, a month or a year) elapsed since the last reading, or period fixed by the contract, the average daily excess demand for that period is determined.

In case the contract requires a higher rate to be paid for an excess demand or one higher than a certain load maximum named in the agreement, the following devices are provided: The base or shank end of the pointer *q* is provided with a pawl or dog 42; and loosely mounted upon the lower end of

the shaft r of the pointer q is a toothed-wheel 43 which meshes with a toothed-wheel 44 fast upon the lower end of a shaft 45 upon the upper end of which is a toothed-wheel 46 which through the toothed-wheel 47 drives the toothed-wheel 48. The latter is fast upon the pointer-carrying shaft 32 and drives the latter and through it the pointers 34 and 40. The ratio of the train of toothed-wheels referred to is such that the pointer 34 is displaced $(N-1)$ times the displacement of the toothed-wheel 43, N being the multiplier which measures the increased rate at which the consumer must pay for the demand in excess of the maximum to which he is entitled at the regular rate. The toothed-wheel 43 is formed with ratchet teeth 50 upon its upper face, and above the latter is mounted a guard-plate 51 which is manually adjustable. As is best shown in the plan view in Fig. 10, the guard-plate 51 does not cover all the ratchet teeth 50. In the initial position of the push-arm n the dog or pawl 42 rests upon the guard-plate 51. At a certain point in its travel determined by the setting of the guard-plate 51, the pawl 42 will ride off the guard-plate 51 and will engage the ratchet-teeth 50 and drive the train of toothed-wheels 43 to 48. The point at which the pawl 42 rides off the guard-plate 51 is that which marks the maximum power-demand to which the customer is entitled without extra charge; and the demand in excess of this maximum is charged for at a rate N times the regular rate or rate at which the power is charged for below this maximum. It will be noted that the travel of the pawl 42 beyond the edge of the guard-plate 51 produces an arc displacement of the pointer 34 $(N-1)$ times the amount of such travel or displacement of the pawl 42 itself beyond the said edge. When the pointer q is returned to its initial position against the pointer 41, the pointer-carrying shaft 32 is by the dogs 35 driven through an equal arc, as hereinbefore described, whereby the pointer 34 is moved through the same arc. From this arrangement of parts it follows that the total displacement of the pointer 34 (that produced by pawl 42 plus that produced by the dogs 35) will be N times the displacement of the pointer q beyond the point which measures the maximum amount of power which the customer is entitled to demand under his agreement without incurring the increased rate. The set pointer 41 may be dispensed with in some cases and the guard-plate 51 used alone. In that event the pointer q will travel from zero position and the travel of the dog 42 will be idle, until it rides off the edge of the guard-plate 51. The edge of the guard-plate is set for the maximum power-demand the customer is entitled to make without incurring the increased rate.

In this arrangement of parts, the adding pointer 34 will indicate the sum of the daily maximum power-demands and in that sum the excesses of the maximum power-demands over the allowable maximum at which a regular rate is charged will appear with N times their actual value.

It is provided by some agreements that at certain defined hours of the day or on certain specified days in the period covered by the bill, the maximum power-demand allowed the consumer without his incurring an increased rate will be different; and it is sometimes provided that the excess power-demands shall be charged for at different rates, according to the particular day or the particular hour of the day on or at which the excess power-demand was made. To meet these cases the guard-plate will be moved periodically within the specified limits, either through a clock or an electromagnet the circuit of which will be opened and closed by a contact clock. The limits of the motion and the time thereof may be varied from day to day by a suitable arrangement of the position and of the shape of the clock contacts and of the tripping arrangement between the clock and the guard-plate 51. Thus, (referring now to Figs. 1^a and 8,) there is shown a pair of toothed disks 60, 61, mounted free to be adjusted relatively to each other upon a shaft 62, which is driven by a clock 63. The teeth 60', 61', of the disks 60, 61, respectively, are formed with cam surfaces. Against the toothed peripheral edge of the cam-disk 60 is pressed, by a coil-spring 64, a shifting-rod 65 mounted free to slide in the guide-plates 66 formed at one end with a lug 67. Similarly, a shifting-rod 65' is pressed by a coil-spring 64' against the toothed peripheral edge of the cam-disk 61, is mounted free to slide in guides 66 and is formed with a lug 67'. The guard plate 51' is carried by a hub or collar 68 (Fig. 1^a) which is provided with a pair of studs 69, 69', with which are adapted to engage the lugs 67, 67', respectively. When the inner end of one of the shifting-rods rides off from one tooth onto the next succeeding tooth, the lug at its other end engages one of the studs on the collar or hub 68 of the guard-plate 51' and moves the latter on its shaft r .

Referring to Fig. 11, there is shown an electrically-controlled device for shifting the guard-plate 51'', wherein a slidable shifting-rod or plunger-rod 65'' is mounted in guides 66'', is provided with stop-lugs 72, 72' and carries a cylindrical mass or block 73 of metal 73 which serves as a plunger-core for the electromagnets 74, 74''. The latter are alternately energized and deenergized by a contact clock 75 on the shaft 76 of which the cam-disks 77, 77' are mounted.

free to be adjusted relatively to each other. On the graduated bar or scale-bar 80 are slidably mounted the posts 79'', 79* the lower ends of which are provided with set-screws 82 for fastening the posts in their adjusted position and against the upper ends of which are adapted to strike the stop-lugs 72, 72', respectively. The shifting-rod or plunger-rod 65* is connected at one end 10 by a link 70 to an ear 69'' formed on the hub 68' of the guard-plate 51''; and the limits of movement of the plunger-rod 65*, which shifts the latter and controls the limits of the latter's oscillations, are varied 15 by moving the posts on the scale-bar 80. The electromagnets 74, 74', are controlled by the cam-disks 77, 77', respectively.

The great utility of the delayed-action circuit-breaking devices shown in Fig. 2 will 20 be clearly understood, when attention is called to the fact that, in order to move the pointers 34, 40, the current must be made to flow through the coil *u* an appreciable time to maintain the magnetic field which causes 25 the rotation of the armature *s* and through it of the pointer-carrying shaft 32, in restoring the pointer *q* to initial position.

It will be observed that the resetting of the push-arm *n* and the pointer *q*, together 30 with the indicating mechanism connected with the latter, is accomplished at a time when the wattmeter is free from connection with the indicator, whereby all counter-torque upon the wattmeter shaft *b* is practically 35 avoided. To accomplish this desirable result, the connection between the wattmeter and my indicator is a clutch connection; and the armature *j* attached to one of the clutch members is cupped (Fig. 9) to obtain a 40 combination of a lifting and turning action by the pole-pieces which lie somewhat above the center or middle line of the armature *j*. The latter is formed with the pointed ears *j'* and the pole-pieces *k* are pointed, whereby 45 it is insured that the push-arm will return accurately to zero position upon resetting. By reducing the magnetic material near the ears *j'* to a minimum the path of the lines of force is so controlled that a rotation 50 through an angle of at least one hundred and twenty degrees is obtained.

A loose pointer 55 is mounted above the dial *w* and its index end projects (as in the case of the tight-fitting hand 41) beyond the 55 edge thereof and into the travel path of the end *v* of the pointer *q* (Fig. 7). The loose pointer 55 will register the maximum power-demand made during the time the indicator has been in use. The pointer 55 is connected with no resetting mechanism. To prevent its accidental displacement by friction of the adjacent rotating parts or otherwise, its base or hub 56 is formed with ratchet teeth 57 with which is adapted to 60 engage the toe of a pawl 58 pivotally

mounted on the pointer 34, should the pointer 55 start to move in a retrograde direction.

I claim:

1. In a meter of the class described, the 70 combination with a wattmeter and means for indicating the maximum power demand during a given interval of time, of a friction clutch which operatively connects said wattmeter and means; and an electromagnetic device for restoring said means to their initial position and simultaneously releasing said clutch, whereby counter-torque upon the wattmeter is avoided. 75

2. In a meter of the class described, the 80 combination with a wattmeter and means for indicating the maximum power demand during a given interval of time, of a two-part clutch which operatively connects said wattmeter and means; a cupped armature 85 attached to one of the parts of said clutch; and electromagnetic devices for raising and turning said armature to release said clutch and restore said means to their initial position. 90

3. In a meter of the class described, the combination with a wattmeter and means for indicating the maximum power demand during a given interval of time, of a two-part clutch which operatively connects said 95 wattmeter and means; an armature formed with ears and attached to one of the parts of said clutch; and electromagnetic devices for raising and turning said armature to release said clutch and restore said means to their initial position, 100 to their initial position, said ears insuring that the final position of said means will be accurately at their zero.

4. In a meter of the class described, the combination with a suitable device bearing 105 graduations, of a pointer movable relatively thereto; a device for actuating said pointer during a given interval of time; and electrically-controlled devices for restoring said device and pointer to their initial position. 110

5. In a meter of the class described, the combination with a suitable device bearing graduations, of a pointer movable relatively thereto; a device for actuating said pointer during a given interval of time; means for returning said pointer to its initial position from the position of its maximum displacement therefrom during a given period; and means for indicating the sum of such maximum displacements. 120

6. In a meter of the class described, the combination of a wattmeter; a maximum-demand indicator; a positioner which is actuated by said wattmeter and which positions said indicator; a pointer-positioning 125 shaft; mechanism which connects said indicator with the latter; and resetting means for restoring said indicator to its initial position; said indicator through said mechanism driving said shaft in one direction. 130

7. In a meter of the class described, the combination with a dial; of a maximum-demand indicator; a wattmeter; a positioner which is actuated by the latter and which 5 positions said indicator; and a stop-pointer which is adapted to be set with respect to said dial and to intercept said indicator when the latter is moved to its initial position thereagainst; the movement of said 10 positioner being idle until the maximum demand exceeds that for which said stop-pointer is set.
8. In a meter of the class described, the combination with a dial; of a maximum-demand indicator; a wattmeter; a positioner which is actuated by the latter and which 15 positions said indicator; a stop-pointer which is adapted to be moved over said dial and to intercept said indicator, the movement of said positioner being idle until the 20 maximum demand exceeds that for which said stop-pointer is set; a pointer-positioning shaft; mechanism which connects said indicator with said shaft; and resetting 25 means for restoring said indicator to its initial position; said indicator through said mechanism driving said shaft in one direction.
9. In a meter of the class described, the combination with a dial; of a maximum-demand indicator; a wattmeter; a positioner which is actuated by the latter and which 30 positions said indicator; a stop-pointer which is adapted to be moved over said dial and to intercept said indicator, the movement 35 of said positioner being idle until the maximum demand exceeds that for which said stop-pointer is set; a pointer-positioning shaft; mechanism driven by said indicator for driving said shaft; and a guard which keeps said mechanism inoperative during a part of the travel of said indicator.
10. In a meter of the class described, the combination with a dial; of a maximum-demand indicator; a wattmeter; a positioner which is actuated by the latter and which 45 positions said indicator; a stop-pointer which is adapted to be moved over said dial and to intercept said indicator, the movement 50 of said positioner being idle until the maximum demand exceeds that for which said pointer is set; a pointer-positioning shaft; mechanism driven by said indicator for driving said shaft; a guard which keeps 55 said mechanism inoperative during a part of the travel of said indicator; resetting means which restore said indicator to its initial position; and connecting devices which connect said indicator to said shaft 60 during the time said resetting means operate, said devices being independent of said mechanism.
11. In a meter of the class described, the combination with a dial, a maximum-demand indicator and a positioner for the 65
- latter; of a pointer-positioning shaft; mechanism driven by said indicator for driving said shaft; and a guard which keeps said mechanism inoperative during a part of the travel of said indicator. 70
12. In a meter of the class described, the combination with a maximum-indicating pointer, of a pair of pawl-and-ratchet mechanisms, one of which is driven by said pointer during its outward travel and the other of which is driven by said pointer during its return travel or movement; and a pointer-carrying shaft driven in the same direction by said pawl-and-ratchet mechanisms. 75
13. In a meter of the class described, the combination with a maximum-indicating pointer, means for actuating the same, and means for resetting the same, of a device for adding the displacements of said pointer and indicating their sum. 80
14. In a meter of the class described, the combination with a maximum-indicating pointer, of a pointer-carrying shaft; and means driven by said pointer for giving to said shaft a rotary movement, said pointer driving said shaft by both its forward and return movements. 90
15. In a meter of the class described, the combination with a dial, a maximum-demand indicator and a positioner for the latter; of a pointer-positioning shaft; mechanism driven by said indicator for driving said shaft; a guard which keeps said mechanism inoperative during a part of the travel of said indicator; and connecting devices which couple said indicator to said shaft during a part of the movement of said indicator. 95
16. In a meter of the class described, the combination with a dial, a maximum-demand indicator and a positioner for the latter; of a pointer-positioning shaft; mechanism driven by said indicator for driving said shaft; a guard which keeps said mechanism inoperative during a part of the travel of said indicator; resetting means for restoring said indicator to its initial position; and connecting devices which couple said shaft and indicator together, while the latter is being reset. 110
17. In a meter of the class described, the combination with a dial, a maximum-demand indicator and a positioner for the latter; of a pointer-positioning shaft; mechanism driven by said indicator for driving said shaft; a guard which keeps said mechanism inoperative during a part of the travel of said indicator; and connections which couple said indicator to said shaft during a part of the movement of said indicator and which are out of gear while said mechanism is operative. 120
18. In a meter of the class described, the combination of a wattmeter; a pointer; 130

- electromagnetic means for displacing said pointer; means for prolonging the flow of current through said electromagnetic means; mechanism actuated by said wattmeter 5 for determining the displacement of said pointer; and electromagnetic means for disconnecting said mechanism from said wattmeter while said pointer is being positioned.
19. In a meter of the class described, 10 the combination of a wattmeter; a pointer; electromagnetic means for displacing said pointer; means for prolonging the flow of current through said electromagnetic means; mechanism actuated by said wattmeter 15 for determining the displacement of said pointer; and electromagnetic means for disconnecting said mechanism from said wattmeter and restoring the former to its initial position while said pointer is being positioned.
20. In a meter of the class described, 20

the combination of a maximum-indicating pointer; a device for displacing the same, said device being free to be reset to its initial position without moving said pointer 25 from its displaced position; a wattmeter for actuating said device; electromagnetic means for disconnecting said wattmeter and device and then resetting the latter to its initial position, leaving said pointer in its 30 displaced position; and electromagnetic means for moving said pointer from its displaced position to its initial position.

In witness whereof I have hereunto set my hand at said Ithaca this sixth day of 35 November, A. D. 1907, in the presence of the two undersigned witnesses.

VLADIMIR KARAPETOFF.

Witnesses:

HENRY H. NORRIS,
H. DIEDERICHS.
